UNITED STATES PATENT OFFICE.

DAVID B. WESTON, OF SHARON, MASSACHUSETTS.

CENTRIFUGAL SEPARATOR.

1,196,056.

Specification of Letters Patent. Patented Aug. 29, 1916.

Application filed December 1, 1911, Serial No. 663,198. Renewed January 19, 1916. Serial No. 73,069.

To all whom it may concern:

Be it known that I, DAVID B. WESTON, a citizen of the United States, and resident of Sharon, Massachusetts, have invented certain new and useful Improvements in Centrifugal Separators, of which the following is a specification.

This invention relates to centrifugal separators intended for use in extracting or separating the solid constituents contained in a body of liquid.

In its essential features the invention comprises a circular separator or drum comprising two opposed conical end walls and having means for introducing the liquid to be treated at one end; and an outlet at the opposite end ports for the escape of solid matter being provided intermediate of the axis and the belt or zone of greatest circumference. Heretofore, it has been proposed to use for this purpose a double conical vessel with the ports for the solid matter arranged at the greatest circumference of the drum; but under high speed rotation difficulties arise in controlling the outlet ports on account of the very considerable pressure at the periphery. This has either necessitated the use of very small ports, which are more likely to become clogged, or else the use of valves which are likely to become disturbed by reason of the great pressure to which they are subjected.

My present invention overcomes these difficulties in that it involves the location of the discharge outlets for the solid matter at points nearer the axis, that is to say, on a shorter radius so related to the zone of largest diameter that the solid matter accumulated in the latter zone is pressed obliquely toward the axis until it reaches the outlet ports, this action tending to greatly relieve the pressure, and therefore to simplify the problem of the proper operation or control of said ports.

In the accompanying drawings I have illustrated different modes of embodying the principles of this invention.

Figure 1 is a central section showing a machine constructed in accordance with my invention; Fig. 2 is a similar view of a modified form having the overhead suspension; Fig. 3 is a similar view of another modification having the underneath support or bearing; Fig. 4 is a plan view of the dia-

phragms or partitions partially subdivid-
ing the interior of the drums; and Fig. 5 is a detail view in section illustrating a modification of the form shown in Fig. 2, in which the passages to the outlet ports are external instead of internal.

In the practice of my invention, according to the form illustrated in Fig. 1, I employ a drum formed of two conical sections a' detachably joined together at their zone of maximum circumference. The upper section a carries an internal conical shield a^2 which extends from a plane above the outlet ports nearly or quite to the larger end of the section a .

To accelerate the rotation of the liquid contents, I provide four radial vanes or partitions b which are joined together at the central axis by means of angle bars b' . These partitions or vanes b are held in place by means of cleats a^3 properly located on the inside surface of the section a' , additional cleats a^4 being suitably located for the same purpose on the inside face of the shield a^2 . This drum is provided with hollow journals a^5 a^6 mounted in suitable bearings, the journal a^5 being connected with a supply pipe a^7 to supply the material to be treated to the lower end of the drum, while the journal a^6 leads to the offtake pipe a^8 for the purpose of conducting away the liquid constituent from which the solid matter has been separated.

The upper section a is provided with ports a^9 , which may be provided with interchangeable or replaceable screw threaded nipples a^{10} by which the size of the openings may be varied. These ports in most cases are preferably closed by valves c , which are actuated by levers c' engaged by a sliding collar c^2 under the control of a hand lever c^3 , by which the valves are operated and controlled.

Under the inlet end and opposed to the inlet ports is arranged a transverse diaphragm or disk d which acts as a deflector to spread the entering liquid outwardly away from the axis of the drum. The drum is surrounded by a casing or curb e into which the solid contents are ejected through the ports a^9 .

The operation of the machine is as follows:—The liquid entering into the pipe a^7 and the hollow journal a^5 passes outwardly around the edges of the deflector or spreader d and under the influence of centrifugal ac-

- tion flows toward the zone of greatest diameter; the solid constituents being heavier than the liquid tend to build up inside this zone of greatest diameter, and when a sufficient amount has been accumulated begins to force its way through the hollow conical passage formed between the shield a^4 and the section a toward the outlet ports a^5 . The lighter liquid constituents must assume, as the machine fills up a position nearer the axis of the machine, and consequently flows out through the hollow journal a^6 into the offtake pipe. After the machine has been operated a sufficient length of time to accumulate a sufficient amount of solid substance, the valves are opened and from that time onward the action is continuous, so long as the machine is kept in operation.
- While I have described the drum as comprising upper and lower sections a a' , it will nevertheless be understood that the arrangement shown in Fig. 1 will operate precisely the same way whether the axis of the machine be horizontal or vertical.
- In Fig. 2, I have illustrated a somewhat simpler embodiment of my invention in which the drum e with its upper and lower conical sections e' e^2 is suspended from an overhead shaft f , in a well-known manner.
- In this case the upper section e' has a relatively larger opening through which pass not only the shaft but also a supply pipe g whose outlet end is carried down adjacent to the lower end of the separator drum.
- This machine is provided with radial vanes e^3 to accelerate the rotation of the liquid constituents.
- On the inside of the lower section are arranged a series of tubular conduits or pipes e^4 which lead to the outlet ports e^5 located intermediate of the central axis and the zone of greatest diameter. The outlet ports may be controlled by valves e operated by lever c' engaged by the sliding collar c^2 which is moved by the hand lever c^3 , just as previously described. At this upper end the drum or receptacle has provided a deflector or discharge plate e^6 over which the escaping liquid flows into the compartment h' of the surrounding curb or casing h . These outlet tubes or conduits e^4 for conducting the solid matter from the zone of greatest diameter back nearer to the axis of the drum may be arranged externally as shown in Fig. 5.
- In this case the drum e^{10} is provided with outlet ports e^{11} nearer to its greatest diameter, and the outlet pipes e^{12} are securely fastened to the outside face, as shown in said Fig. 5.
- In Fig. 3, I have shown how a drum similar to that shown in Fig. 2 may be supported by an underneath bearing, the liquid being supplied through a hollow journal at the bottom and flowing out at the top as in the case of the construction shown in Fig. 2.

In this case the drum e with its upper and lower conical sections e' e^2 is provided with a conical shield m covering the outlet ports and forming an annular conical passage between the inside wall of section e^2 and the shield m in order to guide the solid material from the periphery obliquely toward the axis in order to allow it to escape through the outlet ports e^5 . The deflector d similar to that shown in Fig. 1 serves to spread the liquid flowing in through the hollow inlet journal e^{20} toward the periphery. The delivery plate e^6 and the compartment h and curb h' are the same in construction as that shown in Fig. 2.

The operation of the machines illustrated in Figs. 2 and 3, is as follows:—The liquid to be treated enters at the bottom and tends to move toward the zone of greatest diameter in which action the solid contents are built up inside that zone until sufficient has accumulated to force its way through the passage leading to the outlet ports, the lighter liquid constituents accumulate nearer the center until it begins to flow out through the liquid outlet into the compartment h' into which it is delivered over the plate e^6 and from which it passes into suitable offtake.

What I claim is:

1. A centrifugal separator embracing a rotary receptacle or drum comprising two substantial conical members joined together with their larger diameters in juxtaposition, means for introducing into one end of said drum the liquid to be treated, a deflector for spreading the liquid toward the circumference the opposite end of the drum being provided with outlet ports for the escape of solid matter, said ports being located in the conical wall intermediate of the axis and the periphery of the drum, substantially as described.

2. A centrifugal separator embracing in its construction a separator drum comprising opposed conical walls forming a chamber converging in opposite directions to a common central axis, means for introducing the material to be treated at one end of the drum, outlet ports for the discharge of solid constituents arranged in one conical end wall, in a plane of substantially smaller diameter than the peripheral zone of the drum, and guides secured to the interior face of the conical wall for guiding the solid matter from the peripheral zone to said discharge ports, substantially as described.

3. A centrifugal separator embracing in its construction a rotary separator drum having opposed conical end walls, means for introducing the material to be treated at one apex of the drum, vanes for accelerating the rotation of the liquid so as to press the solid constituents against the inside of

the peripheral portion of the drum, means 5 for conducting the solid matter from said peripheral portion obliquely toward the axis into communication with discharge outlets located intermediate of the axis and the periphery of the drum, substantially as described.

4. A centrifugal separator embracing in its construction a separator drum having 10 opposed conical end walls, means for introducing the liquid to be treated at one end of the drum, outlet ports for the discharge of solid constituents arranged in the conical wall of the drum intermediate of 15 the axis and the periphery of the drum, means for guiding the material from the peripheral portion of the drum inwardly toward said discharge outlets, and a centrally arranged outlet port for the discharge 20 of the liquid from the drum, substantially as described.

5. A centrifugal separator embracing in its construction a drum having opposed conical end walls, means for introducing the liquid to be treated at one end of said drum, 25 an outlet port centrally arranged in the opposite end of said drum, said drum being provided with discharge ports in one coni-

cal end wall, substantially nearer the axis of the drum than is the peripheral portion 30 of said drum, means for guiding the solid matter from the peripheral portion inwardly to said discharge ports, and valves for controlling the discharge of material through said ports, substantially as described. 35

6. A centrifugal separator embracing a drum having opposed conical end walls, a pipe for introducing liquid into the interior of the drum one conical end wall being provided with outlet ports for the discharge of solid matter, a conical shield arranged inside said end wall to form an annular conical passage leading from the peripheral portion of the drum to said outlet ports, and 40 radial vanes for accelerating the rotation of the liquid with the drum, said drum being provided with centrally arranged discharge outlets for the liquid, substantially as described. 45

In witness whereof, I have subscribed the above specification.

DAVID B. WESTON.

In the presence of—
G. A. ROCKWELL,
GEO. N. GODDARD.
